UNITED STATES PATENT OFFICE

2,458,005

ELEVATOR CONTROL APPARATUS

Edward O. Kern, Cedar Falls, Iowa, assignor to
 Wagner Manufacturing Company, Cedar Falls,
 Iowa, a corporation of Iowa

Application June 25, 1945, Serial No. 601,519

4 Claims. (Cl. 177—336)

1

This invention relates to improvements in elevators. More specifically, it relates to means for controlling elevators. Still more specifically, this invention relates to the provision of flashing means to show that an elevator is standing at the top of the elevator shaft.

This means preferably operates only when the elevator is at the top.

This invention also relates to flashing means, which preferably operates only on the green (or down) signal, when the elevator is at the top.

By this means it may be learned if the elevator is at the top when it should be, since an elevator may have left too early or arrived too late.

The invention also relates to flashing means for flashing the light during and after the time the green (or down) light has gone off, and while the car is at the top terminal.

By this means it may be learned when an elevator leaves the top of the shaft.

Another object and advantage of the invention is the provision of such means which is simple and efficient in operation, and is reasonable in cost and simple and practical to produce.

Referring now to the drawings:

Fig. 1 shows the panel of the preferred form.

Fig. 2 shows the upper position of an elevator with the cam and roller-operating switch means; and the dotted lines show the downward position of the elevator, showing the position when the roller leaves the cam.

Fig. 3 is a detailed view of the switch means and switch-operating means.

Fig. 4 is a front view of the interior of the panel with the cover removed.

Fig. 5 is a diagrammatic view of the circuit and switch means used for the flashing means to show when the elevator is standing at the top.

Fig. 6 is a diagrammatic view of a modified form of flashing means, which operates only on the green signal, when the elevator is at the top.

Fig. 7 is a diagrammatic view of another modified form showing the flashing means, which is used during and after the green light has gone on, while the elevator is at the top terminal.

A support 1 may be located at any convenient portion of the building, as, for example, on the first floor.

The support may have a suitable motor 2 provided with a clutch 3 and a driven shaft 4.

Secured to said shaft 4 is a suitable driving means, such as the friction disk 5, with which contacts the adjustable friction disk 6, rigid with

2

the longitudinally adjustable shaft 1, adapted to drive the cylinder 8.

The shaft 7 and the cylinder 8 are substantially as described in Patent No. 1,600,753, and will not be further described in detail.

The system in general may be as described in said patent, or may be varied. The present invention relates to the provision of additional signals.

The dispatching system in general may include a cabinet containing the necessary scheduling device, control unit, including the necessary signal lights, the necessary switches for controlling the lights and the motor of the control unit, provisions for adjusting the round-trip time interval and suitable plugs for cutting cars in and out of service.

The system may be provided with means readily accessible to the starter for sub-dividing the total round-trip time into up time and down time, including means for allowing either more or less than one-half of the round-trip time in either direction.

The dispatching panel preferably includes four signal lights for each car and one starter's call-back button for each car.

The signal lights, located in each control panel 1, shall illuminate simultaneously with those located in the cars and preferably consist of a white light 9 for an up-starting light, a green light 10 for a down-starting light, a red light 11 for the on-time or warning light, and a light 12 for upper terminal control.

Provision may be made in the dispatching cabinet to vary the period between the time that the red or warning light comes on and the time when the white or up light comes on, so as to provide for more or less loading time during this interval.

In Fig. 2 I have shown a cab 13 located in guide rails 14 in the usual manner.

There is also shown mounted on the bottom of the car a roller cam 15, shown in detail in Fig. 3.

The roller may be mounted on a pin 16 in a lever 17, pivotally mounted at 18 in a box 19, secured to the bottom of the car.

The lever preferably has legs 18a and 18b, which may be made integral or may be secured to each other in any suitable manner.

Secured to the lever is a shoe 20, and the lever is normally held in the position, as shown in full lines in Fig. 3, by means of a spring 21, the downward movement of the shoe being limited by means of a stop pin 22.

Also mounted at some convenient point in the elevator hatchway is a cam plate 23, having beveled ends 24 and 25, as shown in Fig. 2.

Adapted to be operated by the shoe are the contacts 26 and 27.

It will be readily understood that when the cab 13 moves downwardly beyond the cam end 25, the roller cam will be in the position shown in Fig. 3 in full lines, and will be in contact with the contacts 26. However, when the car goes upwardly, beyond the cam end 25, the roller will be in the position shown in dotted lines in Fig. 3.

Referring to Fig. 5, there is shown a cylinder 8, which may be operated through a motor 2 connected to a suitable source of power. This may be as set forth in the afore-mentioned patent.

A pilot light 30 may be connected into the circuit, if desired.

The cylinder 8 may have terminal contacts 31, 32, 33, 34 and 35 adapted to contact the signal contacts 36, 37, 38 and 39 on a contact carrying member 40, taking current from a suitable source of supply S.

While the signal system to the cab is illustrated for only one cab and the signal system for the board is illustrated for only two cabs, it will be apparent that the same system may be used for any number of cabs.

It will be understood that the cam plate 23 is located near the top of the elevator shaft. In this way, when the cab reaches the top, the roller 15 will be operated by the cam plate, as heretofore described, to complete a circuit to the flasher 41 through the wires 41a and 41b, as will be readily understood by those skilled in the art.

Normally there will be a steady white light 12 on the control board through the contacts 26 and the wires 41a and 41b, but when the cam roller 15 is operated by the cam plate 23 to the position shown in dotted lines in Fig. 3, the contact at contacts 26 will be broken and the circuit to the flasher 41, through contacts 27, will be completed to flash the light 12 continuously until the cam roller 15 rides off the cam plate 23, when the normal condition will be resumed with the steady white light at 12.

As long as the roller 15 is in contact with the cam plate 23, the roller 15 will be in the dotted line position, shown in Fig. 3, and the upper terminal control light 12 will flash intermittently until after the car leaves the top terminal, so that the starter will know whether or not the cab has left the top terminal immediately after receiving the down-starting signal, which for example, might be the green signal, as described in the afore-mentioned patent.

When the terminal 35 of the cylinder 8 makes contact with the terminal 39, for example, then a circuit is completed for the green or down signal by means of the lines 43 and 44. There is preferably interposed in line 43 a manually controlled push button 60, by means of which the starter may flash a green light in the cab independently of the drum 8.

When this circuit is completed the green signal 45 in the cab 13 will be lighted, as also will be the green signal 10 on the control board.

My invention relates also to flashing means which preferably operate only upon the green or down signal, when the elevator is at the top.

The advantage of this is that it may be learned if the elevator is at the top when it should be, since an elevator may have left too early or arrived too late.

Normally the upper control light 12 will be operated as in Fig. 5.

There may be a wire 47 taken off the wire 43, leading to a relay 48 having return wire 49, referring to Fig. 6.

The relay when energized will attract the switch 48a and close a circuit to the flasher 41 in the cab through wires 50 and 51. In this way, as will be readily understood by those skilled in the art, when the green or starting down light comes on and the roller is engaging the cam plate 23, the signal 12 will flash until the roller passes downwardly beyond the cam plate 23.

Means are also provided for flashing during and after the time the green or down light has gone on. By this means it may be learned when an elevator leaves the top of the shaft.

When the terminal 35 of the cylinder 8 contacts the terminal 39 on the contact carrying member 40 to energize the line 43 to the green light, as in the modification shown in Fig. 6, to complete a circuit with the line 44 to energize the green signals 45 in the cab and 10 on the control board, another circuit will be energized, consisting of the line 47, the relay 48 and the line 49.

The relay 48 when energized will be adapted to pull the switch 48a. When this occurs, the switch 48a will close the circuit to a flasher 41, including the lines 52 and 53.

This circuit also includes a relay 54 (Fig. 7) adapted to release the locking element 55, and the switch 48a is thus returned to inoperative position. Thus means are provided for flashing the flash signal during and after the time the green light has gone on, while the car is at the top terminal, since, after the roller 15 leaves the cam plate 23, the circuit to the flasher will be broken, although the flasher will operate during and after the time the green light has gone on and while the car is at the top when the roller 15 is in contact with the cam plate 23.

Relay 54 is controlled by switch 26 in a circuit including lines 56 and 57.

When the roller 15 rides on the cam plate 23 the switch 27 is closed, partially closing the flasher circuit. This circuit is completed when the switch 48a is closed by the relay 48, which is operated by the green light circuit, as in Fig. 6.

The switch 48a is locked in closed position by the locking pawl 55 until the locking pawl 55 is released, when the switch 26 is closed through energizing the relay 54.

It is believed that the operation of the foregoing will be manifest without further description, but in short there are provided herewith three alternate systems, to-wit:

1. A flashing system when the car is at the top, and which is unconditional upon the green light.

2. A flashing system operating when the car is at the top, conditioned on the green light being on.

3. A flashing system operating when the car is at the top, conditioned on the green light starting, but not dependent upon the continuance of the green light.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. Flashing means for showing that an elevator is standing at the top of an elevator shaft, said means including a cam plate on the elevator shaft at the top thereof and a cam secured to the elevator, operable when the cam on the elevator rides against the cam plate, said cam being adapted to make an electric circuit to cause a 10 flashing signal on a control board, said flashing means being adapted to operate only on a green signal, when the elevator is at the top.

2. Flashing means for showing that an elevator is standing at the top of an elevator shaft, said means including a cam plate on the elevator shaft at the top thereof and a cam secured to the elevator, operable when the cam on the elevator rides against the cam plate, said cam being adapted to make an electric circuit to cause a flashing signal 15 on a control board, said flashing means being adapted to operate only when a green down signal is on, when the elevator is at the top, said means for operating said flashing means including a relay.

3. In an elevator operating system having cars vertically slidable in their respective elevator shafts and the usual indicating and control signals, a flasher signal, a down signal operable from the starting floor of the elevators, and means arranged on said cars and said shafts for operating the flasher signal when a car is positioned at the upper end of the shaft with a circuit to the green down signal closed, one of said means including

a cam plate arranged on the elevator shaft at the top thereof.

4. In an elevator operating signal circuit, including an elevator car in a shaft, a cam plate fixedly mounted in the shaft at the top thereof and positioned to be engaged by a projection of the car, a combination switch box on the elevator car, a roller extending from the switch box adapted to contact the cam plate, a flasher signal arranged on a control board, a circuit connecting the flasher signal to the switch box of the elevator car, means operating the flasher as the circuit thereof is closed by engagement of the roller of the switch box with the cam plate, a down signal, a circuit to the down signal also connected to the said switch box, and communicating means between the circuits wherein the flasher operating means operates only when the down signal circuit is closed.

EDWARD O. KERN.
